COMBINED TOOTHBRUSH HOLDER AND
TOOTH PASTE TUBE DISPENSERArmand A. Iannone, Corona, and Louis La Polla,
East Elmhurst, N. Y.

Application December 8, 1949, Serial No. 131,844

3 Claims. (Cl. 222—98)

1
This invention relates to a combined tooth brush holder and tooth paste tube dispenser.

It is an object of the present invention to provide a tooth brush holder having a tooth paste dispenser built into the same in such a manner that upon a turn of a knob tooth paste will be dispensed from the lower end of the tube and upon a brush held thereunder.

Other objects of the present invention are to provide a combined tooth paste dispenser and brush holder which is of simple construction, inexpensive to manufacture, has a minimum number of parts, compact, easy to operate, of pleasing appearance and efficient in operation.

For other objects and for a better understanding of the invention, reference may be had to the following detailed description taken in connection with the accompanying drawing, in which

Fig. 1 is a perspective view of the combined tooth brush holder and tooth paste dispenser embodying the features of the present invention.

Fig. 2 is a perspective view of the turning knob and the slit tube used for supporting the tooth paste container.

Fig. 2a is a perspective view of the combined holder and dispenser illustrating the manner in which the tooth paste container is inserted upon the slit tube.

Fig. 3 is a fragmentary sectional view taken on line 3—3 of Fig. 1.

Fig. 4 is a sectional view taken on line 4—4 of Fig. 3.

Fig. 5 is a sectional view taken on line 5—5 of Fig. 3.

Fig. 6 is a fragmentary perspective view illustrating the manner in which the rolled tooth paste tube is removed from the tooth brush holder and looking upon the opposite end of the combined holder and tooth paste dispenser, from the end viewed in Figs. 1 and 2a.

Referring now to the figures, 10 represents a jack plate portion having a forwardly extending portion 11 with openings 12 therein for receiving a tooth brush 13. The back wall portion has key hole openings 14 for the securing of the same upon a wall surface. At one end of the forwardly extending portion 11 is a depending skirt portion 15 open at the bottom and adapted to support a tooth paste tube 16.

At one end of the depending skirt portion 15 is a large opening 17 and at the opposite end is a small opening 18. A split tube 21 extends through these openings and an enlargement 22 upon the tube is journaled in the large opening 17 while a flared end of the tube 21 is journaled

in the small opening 18. This tube has a slit 23 for receiving the bottom end 24 of the tooth paste container or tube 16. The bottom end is slid through a slot 25 in the depending portion so that it is disposed within the depending portion. It will be noted that the enlarged sealed bottom end of the tube 16 is completely enclosed by the tube 21, it being inserted as shown in Fig. 2a thru the end slots 25 and 23, and moved horizontally within the depending portion. Due to the fact that the sealed bottom end 24 is of greater thickness than the slot 23, said sealed bottom end becomes anchored therein. Once the winding action of the knot 31 is begun, in order to eject the contents of the tube 16, then slit 23 no longer remains in alignment with slot 25 of the depending portion and tube 16 is automatically locked within the depending portion.

Pressure rollers 26 and 27 are slightly spaced from one another and are journaled in the opposite ends of the depending portion and are adapted to effect the pressure upon the wall of the container 16 as the container is drawn upwardly and rolled upon the split tube 21. With cap 28 removed from the container 16, tooth paste 29 will be extruded and received upon the brush, in the manner as illustrated in Fig. 1.

A knob 31 is secured to the enlarged portion 22 of the tube and can be used for turning the tube. The container 16 will be rolled upon the tube in the manner shown in Figs. 5 and 6. When the contents of the container 16 have been completely discharged, the rolled container 16 can be drawn through the large opening 17 in the manner shown in Fig. 6. The rollers are so placed in relation to opening 17 that no abutment prevents the easy passage of the empty tube 16 that is wound about tube 21. The flared end of the tube 21 can be compressed sufficiently so as to permit the passage of the tube 21 through the small opening 18. The container 16 is accordingly inserted through one end of the depending portion 15 and removed from the other.

While various changes may be made in the detail construction, it shall be understood that such changes shall be within the spirit and scope of the present invention as defined by the appended claims.

Having thus set forth and disclosed the nature of our invention, what is claimed is:

1. A tooth paste dispenser comprising a wall portion, a depending portion connected to the wall portion, a large opening at one end of the depending portion, a small opening at the opposite end of the depending portion, said ends of

the depending portion having slits leading to the openings, a slit tube having a portion adapted to fit the large opening and the end of the tube adapted to fit the small opening, said slit tube and the slits in the depending portion adapted to receive a tooth paste tube, knob means on the tube for turning the same, press rolls for squeezing the tube as it is wound on the slit tube, said tube after having the tooth paste tube wound upon the same being removable through the large opening in the depending portion.

2. A tooth paste dispenser comprising a wall portion, a depending portion connected to the wall portion, a large opening at one end of the depending portion, a small opening at the opposite end of the depending portion, said ends of the depending portion having slits leading to the openings, a slit tube having a portion adapted to fit the large opening and the end of the tube adapted to fit the small opening, said slit tube

10 20

and the slits in the depending portion adapted to receive a tooth paste tube, knob means on the tube for turning the same, press rolls for squeezing the tube as it is wound on the slit tube, said tube after having the tooth paste tube wound upon the same being removable through the large opening in the depending portion, said slit tube being flared at its small end to retain the slit tube against inadvertent outward displacement from the opening containing the tube.

3. A tooth paste dispenser as defined in claim 1, and a laterally extending portion extending over the depending portion and having openings therein for receiving the handles of tooth brushes whereby to support the tooth brushes thereupon.
